[57] **CLAIM**

The ornamental design for a combined beverage cup and holder, as shown.

DESCRIPTION

FIG. 1 is a perspective exploded view of a combined beverage cup and holder showing my new design. FIG. 2 is an elevational view thereof, partly in cross section.

FIG. 3 is an elevational view of a modification of the design of the combined beverage cup and holder of FIG. 1.

FIG. 4 is an elevational view of another modification of the design of the combined beverage cup and holder of FIG. 1.

FIG. 5 is a top plan view of the holder of FIG. 1.

FIG. 6 is an elevational view of the holder of FIGS. 1, 2, 3, 4 and 5.

FIG. 7 is a bottom plan view of the holder of FIGS. 1, 2, 3, 4, and 5.

FIG. 8 is a top plan view of the beverage cup of FIG. 1.

FIG. 9 is an elevational view of the beverage cup of the design of FIG. 1.

FIG. 10 is a top plan view of the beverage cup of FIG. 3.

FIG. 11 is an elevational view of the beverage cup of FIG. 3.

FIG. 12 is a top plan view of the beverage cup of FIG. 4.

FIG. 13 is an elevational view of the beverage cup of FIG. 4.
